ATTORNEY

UNITED STATES PATENT OFFICE.

ROY R. STEVENS, OF FOREST HILLS, PENNSYLVANIA, ASSIGNOR TO THE WESTINGHOUSE AIR BRAKE COMPANY, OF WILMERDING, PENNSYLVANIA, A CORPORATION OF PENNSYLVANIA.

ELECTRIC COUPLER DEVICE.

Application filed September 13, 1927. Serial No. 219,235.

This invention relates to electric train line couplings, and more particularly to a coupling of the type having butt contacts, some of which are fixed relative to the coupling 5 and others movable, such as disclosed in the prior Patent No. 1,601,164 of C. C. Farmer, granted September 28, 1926.

With a coupling of the above type, it is possible, in extreme cases of misalignment 10 of couplings in the act of coupling, for the contacts of counterpart couplings to interlock and thus result in the breaking of the insulation block which carries the contacts, as the couplings move laterally into alignment.

The principal object of my invention is to provide means in an electric train line coupler of the above type for preventing the contacts of counterpart engaging couplings 20 from interlocking.

In the accompanying drawing, the single figure is a sectional view of contact portions of counterpart couplings, showing my invention applied thereto.

25 In view of Patent No. 1,601,164, it is only deemed necessary to a clear understanding of the present invention to show a portion of the insulation block 40 of counterpart couplings, the insulation block 40 at the left of the drawing, having the relatively movable contacts 41' and the other insulation block 40 having the stationary contact members 41.

According to my invention, the end stationary or fixed contact member 41" is provided with a lateral extension A and one corner of each contact is beveled off, as shown at B.

It will be understood that the electric train line couplings are carried by car couplings 40 of the type in which there is a relative movement of the car coupling heads in the act of coupling and that this relative lateral movement is therefore present in the electric train line couplings in the act of coupling.

45 In the drawing, the counterpart coupling portions are shown in an extreme lateral position, such that without my invention, the lower end movable contact 41' might move longitudinally past the end of the lower end 50 movable contact 41", and thus cause an interlocking of the contacts, so that lateral movement of the couplings would cause breakage of the parts.

By providing the extension A on the end stationary contact 41", the lower end movable contact 41' is prevented from moving longitudinally past the contact face of the lower end stationary contact 41". The interlocking of the other intermediate contacts is prevented because the space between adjacent contacts is of less width than the width of the contacts, so that a contact of a coupling cannot enter the space between adjacent contacts of a counterpart coupling.

It will be understood that the coupling 65 may be provided with a plurality of horizontally disposed rows of contacts, so that there will be an end fixed contact 41" for each horizontal row. In such case, each of the end fixed contacts will be provided with an extension A.

Slight irregularities in individual contacts is provided for and lateral movement is facilitated by beveling off the engaging covers of the contacts, as shown at B.

While one illustrative embodiment of the invention has been described in detail, it is not my intention to limit its scope to that embodiment or otherwise than by the terms of the appended claims.

Having now described my invention, what I claim as new and desire to secure by Letters Patent, is:

1. An electric train line coupling having contacts, some of which are fixed and others of which are movable relatively to the coupling, the movable contacts of one coupling being adapted to engage the fixed contacts of a counterpart coupling, and one of the fixed contacts having a lateral extension 85 adapted to be engaged by one of the movable contacts of a counterpart coupling.

2. An electric train line coupling provided with contacts adapted to engage contacts of a counterpart coupling, some of the contacts being stationary relatively to the coupling and others longitudinally movable, one of the stationary contacts having a lateral extension engageable by a movable contact of a counterpart coupling in the act of coupling.

3. An electric train line coupling provided with contacts adapted to engage contacts of a counterpart coupling, some of the contacts being stationary relatively to the coupling and others longitudinally movable, the outermost stationary contact having a lateral ex-

tension engageable by a movable contact of a counterpart coupling when the contacts are laterally displaced in the act of coupling.

4. An electric train line coupling having contacts, some of which are fixed and others of which are movable relatively to the coupling, the movable contacts of one coupling being adapted to engage the fixed contacts of a counterpart coupling, and at least one of the fixed contacts having a lateral extension adapted to be engaged by one of the movable contacts of a counterpart coupling.

5. An electric train line coupling having contacts, some of which are fixed and others of which are movable relatively to the coupling, the movable contacts of one coupling being adapted to engage the fixed contacts of a counterpart coupling, and one or more of the fixed contacts having a lateral extension adapted to be engaged by one of the movable contacts of a counterpart coupling. ¹⁵

In testimony whereof I have hereunto set my hand.

ROY R. STEVENS.
